DRINKING WATER DISPENSER FOR PETS

Bruce A. Ogilvie, Highland, Calif., assignor of one-half to James Linn Rodgers, Whittier, Calif.

Filed Jan. 29, 1962, Ser. No. 68,551

Term of patent 14 years

(Cl. D12—2)

FIGURE 1 is a side elevation of a drinking water dispenser for pets, embodying my new design;

The unshown side is a mirror image of the side shown in FIGURE 1. The dominant features of the design reside in the portions shown in solid lines.

I claim:

The ornamental design for a drinking water dispenser for pets, substantially as shown and described.
